UNITED STATES PATENT OFFICE.

EUGÈNE SCHNEIDER, OF LE CREUZOT, FRANCE.

SUBMARINE MINE.

1,073,291.

Specification of Letters Patent. Patented Sept. 16, 1913.

Application filed February 14, 1913. Serial No. 748,414.

To all whom it may concern:

Be it known that I, EUGÈNE SCHNEIDER, of Le Creuzot, France, have invented new and useful Improvements in Submarine Mines, which is fully set forth in the following specification.

This invention relates to submarine mines.

Carteron's United States Patent No. 1,039,254, issued 24 September, 1912, describes a submarine mine adapted to be moored from a submersible vessel, with which object it is provided with a series of devices producing the following effects: 1. They insure a positive buoyancy of the mine 15 constituted by the float, the anchor and the regulating weight, so long as these three elements are united to a fixed station upon the submersible vessel, in such a manner that the mine as a whole when released from 20 the submerged vessel leaves the latter and rises toward the surface. 2. After the release of the mine these devices effect the separation of the three elements, and the destruction of the buoyancy (effected by 25 suitably ballasting the elements) these operations being, however, retarded in such a manner that the elements as a whole are afforded sufficient time to rise to the surface or in proximity to the surface, before the 30 three elements begin to separate. 3. In a particularly advantageous embodiment of the invention the safety salt blocks of the firing device are protected from the water during submerged navigation and the water 35 is not allowed to come into contact with the salt until after the mine has been released from the submersible vessel. In accordance with the invention described in the Carteron patent referred to above, these effects were 40 obtained by the following essential auxiliary members: The first effect was obtained by means of water ballast chambers (the auxiliary reservoir of the float, and the caissons of the anchor) maintained closed by valves, 45 so long as the three mine elements are assembled on the deck of the vessel. The second effect was obtained by an immersion regulating weight having a retarded fall and a device retarding the opening of the valves 50 of the caissons—the opening of all the valves being effected by the rocking of the mine in the water around its center of gravity as soon as it has been released from the vessel. With this object the mine was 55 locked in an inverted position upon the deck of the submersible vessel. The third effect

was obtained by inclosing the salt blocks in the auxiliary reservoir of the float.

The present invention has for its object an improvement of the mine disclosed by 60 the Carteron patent referred to above. This improvement results in a very considerable simplification of the characteristic means enumerated above.

It consists: (1) of a modified arrangement 65 of the valves for the ballast reservoirs, which permits of the retarded opening of the valves without necessitating the rocking of the mine about its center of gravity and consequently enabling the mine to be locked 70 in its normal uninverted position, and (2) some modifications in the forms and arrangements of the several parts.

In order that the said invention may be clearly understood and readily carried into 75 effect, the same will be described more fully with reference to the accompanying drawings, in which:—

Figures 1 and 2 are sectional elevations (at right angles one to the other) of a mine. 80 Figs. 3 and 4 are views of details and Fig. 5 shows the various positions assumed after launching.

As in the construction described in the Carteron patent referred to above, the improved form of mine comprises the following characteristic auxiliary members: 1. An auxiliary reservoir 1 inclosed in the float *a*; this reservoir is provided with a valve *s* and protects two safety devices *x* (salt block devices) for the firing mechanism (Fig. 1). 85 2. Two caissons *r*, *r* belonging to the anchor *b* and each provided with valves 9. 9. 3. An immersion regulating weight *d* provided with a fall retarder (Figs. 1 and 2). 95

The counterweighted valve device is replaced by the following (Figs. 3 and 4): Each of the anchor caissons *r*, *r*, and the auxiliary reservoir 1 of the float are closed by a plug *s* shown in Figs. 3 and 4. This 100 plug *s* has a conical bearing surface *s'* which rests upon a conical seat formed in the screw plug or socket *s'* carrying the plug. The plug is held in place upon its seat by a strap of solder *s*² located in a groove *s*³, 105 which is provided for this purpose, upon the periphery of the plug. The plug ends in an eye *s*⁴. The screw plug or socket *s'* in which the plug *s* is fitted has a central passage *s*⁵ through which the water is able 110 to pass as soon as the plug has been torn away. It can be screwed with the inter-

position of a washer s^6 , upon an appropriate housing on the caisson or of the auxiliary reservoir of the float and sealed therein by solder strips s^2 .

5 The anchor (Figs. 1 and 2) is of different formation from that described in the patent referred to above. The two caissons r , r are cylindrical reservoirs, secured in standards b^6 rising from a cast iron sole plate b' .
10 On top of these caissons and fast thereto are mounted brackets b^2 supporting a chair frame b^8 , on which the float a is seated. The sole plate b' is also provided with other standards b^7 , in which is supported a reel e carrying a mooring cable c and having a ratchet wheel b^8 adapted to be engaged by a spring retained locking pawl g mounted on one of the standards b^7 . A cross piece b^3 riveted to the two caissons r , serves as point 15 of attachment for the fall retarder of the immersion regulating weight d . For a detailed description of this fall retarder, reference is had to U. S. Patent 1,039,254 referred to above, but briefly stated it consists 20 of a piston d^6 working a piston channel in weight d , the piston being provided with a piston rod having a head which is normally gripped by jaws d^3 pivotally supported at the end of a rod d^2 which is secured at its 25 upper threaded end to cross piece b^3 . The function of this device is to retard the fall of weight d after the mine is released, as described below. The sole plate b' carries at its lower part an eye b^4 which serves for 30 locking the mine to the deck by means of a bolt k .

The immersion regulating weight d (Figs. 1 and 2) is of the same formation as that described in Carteron's patent referred to 35 above. It is provided with the same fall retarder device, with pin, claws, glycerin cylinder and piston. The pin can be attached to the middle of the cross piece b^3 . The auxiliary reservoir 1 of the float a (Fig. 1) receives the two salt block safety devices x described in the said patent, these devices locking the firing mechanism so long as the salt blocks have not been dissolved in the water.

40 Thus modified the mine can be installed upon the deck of the submersible vessel in its normal position (with the anchor downward) as shown in Figs. 1 and 2. It is held there by a compressed air actuated bolt k , similar to that indicated in the patent in question; this bolt engages in the eye b^4 of the sole plate b' and can be controlled from the interior of the vessel. The plugs s , 9 and 9 are placed in position on their conical 45 seats upon the reservoir 1 and upon the caissons, r r respectively and sealed therein by solder strips s^2 ; they thus insure the watertightness of the auxiliary reservoir of the float and of the caissons of the anchor. In 50 these conditions, the reservoirs 1 and r r

being free from water the mine as a whole possesses buoyancy; furthermore, the salt blocks inclosed in the auxiliary reservoir 1 of the float are protected from the water and block the firing mechanism.

70

The soldered plug s of the auxiliary reservoir of the float (Fig. 1) is attached by the intermediary of a link t to a length of cable t' the other end of which is attached to an eye t^2 fixed to the part b^2 of the anchor. In this position the cable t' is not taut.

75

Each of the soldered plugs 9 , 9 of the caissons r of the anchor is attached by the intermediary of a link z to a cable z' the other extremity of which is attached to an eye z^2 fixed to the float a . The two lengths of cable z' are not taut in this position.

80

85 The immersion regulating weight d (Figs. 1 and 2) is placed upon a recess j in the deck. It is provided with its retarding device, the pin of which is attached to the middle of the cross piece b^3 . It is also attached, as in the Carteron patent referred to above, to an immersion regulating line f 90 which is wound upon it, the other end of this line being attached to the locking lever g of the winch.

95

The mine is released during the submersion of the vessel merely by drawing back the bolt k . The released mine as a whole starts from the position I (Fig. 5) rises toward the surface to the position II and reaches the surface in the position III. The immersion regulating weight d would 100 have a tendency to remain upon the deck but is carried along with the mine owing to its fall retarder, which does not permit of its release from the claws d^3 of the pin d^2 until the expiration of a certain time. This 105 time is sufficient to enable the mine to rise to the surface or in proximity to the surface and for the submersible vessel to leave the spot (Fig. 5, position III). At the end of this period, the immersion regulating 110 weight d is released; it falls, unwinds the immersion regulating line f and exerts traction upon the locking lever. The winch is released and the anchor (which although 115 the caissons r are empty, has a certain weight in the water) descends and unwinds its cable c , while the float a remains on the surface. At a given moment, the lengths of cable t' z' z' are taut (positions IV and V) and the soldered plugs are torn out. 120 The anchor continues its descent, the caissons of the anchor become filled with water and the mooring is completed in the ordinary manner (positions VI and VII).

125

It will be seen that the valve arrangement does not permit of the opening of the ballast reservoirs until the immersion regulating weight has descended, it subordinates the opening of the valves to the fall of the immersion regulating weight. It 130

therefore insures certainty in the opening of the valves with a certain amount of retardation from the time of releasing the mine.

5 What I claim and desire to secure by Letters Patent of the United States is:

1. A submarine mine adapted to be launched from a submarine vessel and comprising a float, an anchor and a regulating weight normally superimposed in the order named for launching, cables connecting said parts, said float and anchor each provided with a ballast reservoir having a valved closure, and connections between said valves and the anchor and float respectively and adapted to uncover said parts when said parts separate on launching.

2. In a submarine mine adapted to be launched from a vessel under water, the combination of a buoyant torpedo and an anchor, each having a ballast chamber provided with a sealed closure, a cable connecting said parts and flexible connections between said seals and said anchor and float respectively and retarding means on the operation of which said parts separate and cause said connections to break the seals.

3. In a submarine mine, the combination of a buoyant torpedo having a ballast cham-

ber provided with a sealed closure, a separable anchor for said torpedo and means for breaking said seal operable by the separation of said anchor from said torpedo.

4. In a submarine mine, the combination of a buoyant torpedo provided with a ballast chamber having a port normally closed by a solder sealed plug, a separable anchor for said torpedo and connections between said plug and anchor for breaking said seal on the separation of said torpedo and anchor.

5. In a submarine mine, the combination of a buoyant torpedo and an anchor, each of said elements being provided with a ballast chamber having a port normally closed by a solder sealed plug, a cable for connecting said torpedo and anchor, a regulating weight on the release of which said anchor separates from said torpedo, and means successively operating to release said plugs.

In testimony whereof I have signed this specification in the presence of two subscribing witnesses.
